**ADJUSTMENT LOCK FOR PRINTING
PRESS ROLLERS**

Hans Grünig, Bern, Switzerland, assignor to Maschinenfabrik Winkler, Fallert & Co., AG., Bern, Switzerland
Filed June 3, 1964, Ser. No. 372,204
Claims priority, application Sweden, June 28, 1963,
7,204/63

9 Claims. (Cl. 101—216)

This invention relates to inking arrangements for printing presses and, more particularly, to novel means for adjusting the position of an inking roller in a printing press and for permitting removal of the inking roller from the printing press without disturbing the adjusted setting thereof.

In inking arrangements for book presses, letter presses, offset presses, and other printing presses, inking rollers are arranged in contact with one or more so-called friction rollers. The latter have covers of elastic material, such as rubber, gelatin, plastic, etc. The inking rollers cannot be fixedly mounted in the frame of the printing press because the inking rollers, which are subject to wear, must be adjustable relative to the friction roller or rollers to compensate for variations in diameter of the inking roller. It is also desirable, when the machine is at rest, that the inking rollers do not remain in contact with the printing rollers or with the form, so as to prevent deformations in the elastic material such as might occur if the inking roller is maintained in contact with a stationary roller over a long interval. Thus, the inking rollers, and particularly their mountings, must be so designed that they may be set off and disassembled from the printing press without any difficulty.

Various arrangements have been proposed for adjustably fixing printing rollers in the frame of a printing press. In one known arrangement, the locking adjustable support is positioned in the frame and has a bearing journal projecting on the inner side of the frame wall. Adjustment of the inking roller position can be effected from the outside of the machine frame. However, such adjustment is cumbersome inasmuch as the contact of the inking roller with the friction roller or rollers, or with the form, on the inside of the frame, must be checked while the adjustment is being effected from outside the frame.

In another recently developed locking adjustable support for inking rollers, the support is arranged on the inside of the machine frame and adjusted from the inside, rather than from the outside of the frame where the driving wheels for the friction rollers preferably are arranged. This latter support includes an axially displaceable eccentric bearing pin, which is axially adjusted by means of a rack and a manually operated pinion. Fine adjustment of the inking roller is obtained by angular adjustment of the eccentric bearing pin inside of the machine frame.

Known locking adjustable support arrangements for inking rollers require a great deal of space and are relatively expensive. A further disadvantage thereof is that it is very difficult, after removal of the inking roller from the printing press, to reposition it into the previously adjusted position.

An object of the present invention is to provide a support for a printing press roller, and which support may be adjusted and locked in adjusted position, but which is simple in construction and simple to operate.

Another object of the invention is to provide a locking adjustable support for a roller of a printing press, and providing for ready removal of the roller from the printing press without disturbing the adjusted setting of the roller when the latter is re-inserted into the printing press.

2

A further object of the invention is to provide a locking adjustable support for inking rollers of printing presses and which is readily adaptable to situations where the inking roller is used with a single friction roller or with a pair of friction rollers, and which further provides for easy adjustment of the degree of contact of the inking roller with either one of a pair of friction rollers.

Still another object of the invention is to provide a locking adjustable support for inking rollers of printing presses by means of which the inking roller may be used in operative relation with other rollers having a contact over the full circumference thereof or which have a contact over only part of their circumference, and which is readily adaptable for use with printing forms having less than 360° extent, such as the plates applied to the cylinders or rotary letter presses or the like.

In accordance with the present invention, and to fulfill the foregoing objects, the locking adjustable support of the present invention comprises an eccentric sleeve which is angularly adjustable about a guide pin or trunnion. This sleeve has a first arcuate slot or gap arranged to permit ready removal of an inking roller from the support, and is also formed with a circumferentially extending slot arranged to receive a locking or clamping pin or bolt. The eccentric sleeve further has a longitudinally extending bore receiving a projecting locating pin.

An adjusting ring is angularly adjustable on the guide trunnion and has set screw means or the like for locking it in an angularly adjusted position. This adjusting ring has a bore receiving a projected locating pin which can contact the locating pin on the eccentric sleeve, when the adjusting ring is adjusted angularly relative to the eccentric sleeve, whereby the adjusting ring can be locked, by its set screw means, in a position maintaining the adjusted position of the eccentric sleeve. Thereby, when the eccentric sleeve is unlocked and rotated to a position where the inking cylinder may be removed from the press, upon re-insertion of the inking cylinder into the adjusting sleeve, the latter can be rotated until the two locating pins abut and then clamped into position. Thus, the previously adjusted position of the inking roller with respect to the cooperating friction roller or friction rollers is maintained at all times.

The clamping means for the eccentric sleeve preferably includes a ring rotatably mounted on the eccentric sleeve and carrying a pin extending through the circumferentially extending slot of the eccentric sleeve and threaded into the mounting trunnion. Upon tightening of the locking bolt or pin, this ring compresses the eccentric sleeve against the guide trunnion to hold the eccentric sleeve in adjusted position.

For an understanding of the principles of the invention, reference is made to the following description of typical embodiments thereof as illustrated in the accompanying drawings.

In the drawings:

FIG. 1 is a somewhat schematic diametrical sectional view of the eccentric sleeve and associated parts for adjusting the position of the inking roller;

FIG. 2 is a view similar to FIG. 1 illustrating the sleeve rotated through 90°;

FIG. 3 is a view similar to FIG. 1, but illustrating the eccentric sleeve rotated through 180°;

FIG. 4 is a diametrical sectional view taken essentially on the line I—I of FIG. 5;

FIG. 5 is an axial sectional view through a locking adjustable support embodying the invention;

FIG. 6 is a plan view, with parts being shown in section, of the locking adjustable support of FIGS. 1-5

and illustrating the latter as positioned upon a flange which is angularly adjustable to set the degree of contact of the inking cylinder with either one of a pair of friction rollers;

FIG. 7 is an elevation view corresponding to FIG. 6;

FIGS. 8 and 9 are views similar to FIG. 4 illustrating an alternative embodiment of the invention and showing two different angularly adjusted positions of the eccentric sleeve;

FIG. 10 is an axial sectional view through the locking adjustable support shown in FIGS. 8 and 9; and

FIG. 11 is an elevation view of the locking adjustable support shown in FIGS. 8 and 9, and with a part in section being taken in a plane at right angles to the plane of FIG. 10.

Referring first to FIGS. 1-5, the locking adjustable support for inking rollers of printing presses includes a substantially fixed guide pin or trunnion 1 which is formed with diametrically slotted guide means 2, known per se, into which an anti-friction bearing 4 for an inking roller axle 3 may be mounted. An eccentric sleeve 5 and an adjusting ring 6 are mounted for angular adjustment on guide trunnion 1, and a sleeve 7 is concentric with the external surface of sleeve 5 and is angularly adjustable thereon. It should be understood that the diametrically slotted guide means 2 of trunnion 1 could also receive the axle of an inking roller which is not supported in anti-friction bearings.

Eccentric sleeve 5 has a segmental recess 8 at its inner end, by means of which the inking roller shaft and its bearing means, if any, may be removed from the support and re-introduced therewith. Sleeve 5 is further formed, as best seen in FIGS. 4 and 5, with a circumferentially extending slot 9 extending through a little more than 180°. In a manner to be described, this slot 9 limits the angular adjustment of sleeve 5 to about 180°. The outer end of sleeve 5 is formed with a groove extending peripherally thereof and opening toward the outer end of sleeve 5. A bore 10 opens into this peripheral groove and receives a locating pin 11 which projects into the groove. The adjusting ring 6 is mounted in substantial axial abutment with the outer end of eccentric sleeve 5, and ring 6 is formed with a bore 12 in which is seated a locating pin 13 extending into the aforementioned peripheral groove in the end of sleeve 5.

Ring 7 is seated on a reduced diameter portion of eccentric sleeve 5 and is positioned between a shoulder formed on sleeve 5 and a side surface of ring 6. Ring 7 is formed with a radial opening 14 through which extends a locking bolt, screw or pin 15. The shank of element 15 furthermore projects, with clearance, through the circumferentially extending slot 9 of the eccentric ring 5, and is threaded for engagement into a threaded radial bore 16 in guide trunnion 1. Ring 7 has an axial extent such as to close the slot 9.

The outer end of pin or trunnion 1 is formed with a circular or annular lug 17, and an axial passage extends through the outer end of trunnion 1, being enlarged adjacent the inner end of the trunnion. This axial passage receives a mounting or locking bolt 20.

Referring to FIG. 6, if the locking adjustable support for an inking roller, as shown in FIGS. 1-5, is to be used with an inking roller which is to be maintained in engagement with two friction rollers, the extension 17 of trunnion 1 is seated in a circular recess 19 in the outer surface of flange or plate 18, and the inner end of locking bolt 20 is threaded into a threaded bore concentric with the recess 19. A bush 21 is seated in a circular opening in flange 18, this opening being offset from the recess 19. A bolt or screw 22 is seated in bush 21 and secures the locking adjustable support to the frame or side wall 23 of the printing press, bolt 22 being threaded into a suitable threaded bore in the wall 23. Thus, the flange or plate 18 is adjustable about the axis of bolt 22 through the medium of the bush 21. Thereby, the inking roller

5

can be brought into firmer contact with one friction roller than with the other, if so desired. The flange or plate 18 can be tightened in the desired position by means of a bolt or screw 24 which extends through a slot 25 in plate 18 adjacent the free end thereof.

On the other hand, and referring to FIG. 5, if the locking adjustable inking roller support is to be used with an inking roller which is engaged with only one other roller, a circular spacer or the like 26 can be interposed between the outer end of trunnion 1 and the wall 23 of the printing press. It should be understood, however, that the locking adjustable inking roller support may be secured directly to the wall of the printing press, without the interposition of the spacer, if the axle of the inking roller is correspondingly extended or elongated.

The operation of the locking adjustable support for inking rollers will be clear from FIGS. 1-5. When eccentric sleeve 5 is in the position shown in FIG. 1, the inking roller can be introduced into or removed from its locking adjustable support. By turning the eccentric sleeve counterclockwise from the position shown in FIG. 1 to the position in FIGS. 2 and 3, the inking roller is adjusted upwardly or toward the friction roller or rollers. When the inking roller is in the desired position, eccentric sleeve 5 is clamped in its adjusted angular relation by tightening locking screw 15. Set screw 27 is then loosened, and adjusting ring 6 is turned sufficiently far that locating pin 13 will engage locating pin 11. Adjusting screw 27 is then re-tightened to lock ring 6 in its angularly adjusted position with pins 13 and 11 in engagement.

If it is necessary to remove the inking roller, locking screw 15 is loosened so that eccentric sleeve 5 may be turned into the position shown in FIG. 1. When the inking roller is re-inserted, eccentric sleeve 5, after such re-insertion, is turned until locating pins 11 and 13 are again in contiguous juxtaposition. The inking roller is now in exactly the same adjusted position as before its removal, and locking screw 15 is re-tightened to lock sleeve 5 in position.

If it is necessary to adjust the position of the inking roller, locking screw 15 and set screw 27 are loosened. Eccentric sleeve 5 is then turned to attain the desired adjustment of the inking roller, after which locking screw 15 is re-tightened. Adjusting ring 6 is then turned until locating pins 13 and 11 are again in juxtaposition, after which set screw 27 is re-tightened.

The embodiments of the locking adjustable supports so far described are suitable only in the case where the inking rollers are to be pressed against other rollers having an uninterrupted circumference or a contact surface which extends through a full 360°. By a slight modification, involving a few additional elements, it is possible to modify the locking adjustable supports so that the inking roller may be pressed against printing forms having an interrupted circumference such as, for example, the plate-type cylinders of rotary letter presses equipped with stereo-type plates, or offset cylinders provided with clamping grooves.

Referring to FIGS. 8-11, a T-shape slot 28 is formed in guide pin or trunnion 1, and slidably receives a T-shape slide 29 having a forward extension 30 overlying the anti-friction bearing for the inking roller. Extension 30 is arcuate to conform to the circular outer surface of the outer race of the anti-friction bearing. Slide 29 is formed with a radial recess 31 from the inner end of which extends a very small diameter radial bore 32. Recess 31 serves to seat suitable relatively strong spring means, such as cup springs 33, and a guide pin 34 extends axially of recess 31 and has a slidable fit in its extension 32. A slide 35 is secured to the outer end of pin 34 and is biased outwardly by the spring 33. Axial displacement of slide 35 is prevented by a segment 36 secured 60 to screw 37 to extension 30 of slide 29.

The interaction between slides 29 and 35 provided by the interposed springs 33 results in slides 29 and 35 jointly holding the inking roller in the position adjusted by angular adjustment of eccentric sleeve 5. However, springs 33 provide for the inking roller to adjust itself to variations or interruptions in the circumference of rollers against which the inking roller is pressed. The arrangement of FIGS. 8-11 also provides for the inking rollers being removed from the locking adjustable support and re-inserted therein in the previously adjusted position, although the means for doing this are shown in detail in FIGS. 1-5 and have not been shown or described in detail in the embodiment of FIGS. 8-9 although they are included therein as will be apparent upon inspection of FIGS. 8-11.

To facilitate angular adjustment of eccentric sleeve 5 and adjustable ring 6, the peripheries of these two elements are provided with radial recesses such as 38 and 39, respectively, which can receive a spike, mandrel or the like for operation of the sleeve 5 and the ring 6.

It should be noted with respect to each of the embodiments of the invention that the parts are simple and inexpensive to produce, and the assembly is greatly simplified as compared to the prior art. Additionally, adjustment is greatly facilitated.

While specific embodiments of the invention have been shown and described in detail to illustrate the application of the principles of the invention, it should be understood that the invention may be embodied otherwise without departing from such principles.

What is claimed is:

1. A locking adjustable support, for printing press rollers or the like, comprising, in combination, a substantially cylindrical trunnion arranged to be fixedly secured relative to the press frame, the inner end of said trunnion having a diametric slot arranged to conformingly slidably receive the bearing means of a press roller; an eccentric sleeve rotatably mounted around the external periphery of said trunnion and having a circular surface portion on its axially inner end eccentric to said trunnion and extending axially of said slotted inner end of said trunnion for supporting engagement with a bearing means in said slot to adjust said bearing means along said slot responsive to relative rotation of said sleeve on said trunnion to an adjusted position the side surfaces of said slot continuously engaging diametrically opposite portions of said bearing means throughout the range of adjustment; said sleeve circular portion having a peripherally extending slot opening axially through the inner end of said sleeve and of an arcuate extent substantially equal to that of said diametric slot whereby, when said sleeve is angularly adjusted to a predetermined position in which said slots are radially aligned, a bearing means may be inserted into and removed from said diametric slot; and position setting means angularly adjustable on said trunnion in accordance with the adjusted position of said sleeve and cooperable with said sleeve to re-set the adjusted position of the latter when said sleeve has been moved from its adjusted position to said predetermined position and then returned toward said adjusted position.

2. A locking adjustable support, for printing press rollers or the like, comprising, in combination, a substantially cylindrical trunnion having an outer end arranged to be fixedly secured relative to the press frame, the inner end of said trunnion having a diametric slot arranged to conformingly slidably receive the bearing means of a press roller; an eccentric sleeve rotatably mounted around the external periphery of said trunnion and having an axially inner circular surface portion eccentric to said trunnion and extending axially of said slotted inner end of said trunnion for supporting engagement with a bearing means in said slot to adjust said bearing means along said slot responsive to relative rotation of said sleeve on said trunnion to an adjusted position; the side surfaces of said slot continuously engaging diametrically opposite portions of

said bearing means throughout the range of adjustment; said sleeve circular surface portion having a peripherally extending slot opening axially through the inner end of said sleeve and of an arcuate extent substantially equal to that of said diametric slot whereby, when said sleeve is angularly adjusted to a predetermined position in which said slots are radially aligned, a bearing means may be inserted into and removed from said diametrical slot; means operable to lock said sleeve against rotation relative to said trunnion; and position setting means angularly adjustable on said trunnion in accordance with the adjusted position of said sleeve and cooperable with the latter to re-set said angularly adjusted position thereof when said sleeve has been angularly adjusted from its adjusted position to said predetermined position and return toward said adjusted position.

3. A locking adjustable support, for printing press rollers or the like, comprising, in combination, a substantially cylindrical trunnion having an outer end arranged to be fixedly secured relative to the press frame, the inner end of said trunnion having a diametric slot arranged to conformingly slidably receive the bearing means of a press roller; an eccentric sleeve rotatably mounted around the external periphery of said trunnion and having an axially inner circular surface portion eccentric to said trunnion and extending axially of said slotted inner end of said trunnion for supporting engagement with a bearing means in said slot to adjust said bearing means along said slot responsive to relative rotation of said sleeve on said trunnion to an adjusted position; the side surfaces of said slot continuously engaging diametrically opposite portions of said bearing means throughout the range of adjustment; said sleeve circular surface portion having a peripherally extending slot opening axially through the inner end of said sleeve and of an arcuate extent substantially equal to that of said diametric slot whereby, when said sleeve is angularly adjusted to a predetermined position in which said slots are radially aligned, a bearing means may be inserted into and removed from said diametrical slot; means operable to lock said sleeve against rotation relative to said trunnion; position setting means angularly adjustable on said trunnion in accordance with the adjusted position of said sleeve and cooperable with the latter to re-set said angularly adjusted position thereof when said sleeve has been angularly adjusted from its adjusted position to said predetermined position and return toward said adjusted position; and interengageable means on said trunnion and on said sleeve effective to limit angular movement of said sleeve relative to said trunnion.

4. A locking adjustable support, for printing press rollers or the like, comprising, in combination, a substantially cylindrical trunnion arranged to be secured relative to the press frame, the inner end of said trunnion having a diametric slot arranged to conformingly slidably receive the bearing means of a press roller; and eccentric sleeve rotatably mounted on said trunnion and having a circular surface portion on its axially inner end eccentric to said trunnion and extending axially of said slotted inner end thereof for engagement with a bearing means in said slot to adjust said bearing means along said slot responsive to relative rotation of said sleeve on said trunnion to an adjusted position; said sleeve circular portion having a peripherally extending slot opening axially through the inner end of said sleeve and of an arcuate extent substantially equal to that of said diametric slot whereby, when said sleeve is angularly adjusted to a predetermined position in which said slots are radially aligned, a bearing means may be inserted into and removed from said diametric slot; a first locating pin projecting from the axially outer end of said sleeve; a ring rotatably mounted on said trunnion adjacent the axially outer end of said sleeve; a second locating pin on said ring projecting toward said eccentric sleeve and into the path of movement of said first locating pin; means releas-

ably locking said eccentric sleeve in its adjusted position; and means releasably locking said ring in its adjusted position; whereby, after movement of said eccentric sleeve to its adjusted position and locking thereof, said ring may be rotated until said locating pins are in abutment; said ring thereupon being locked so that, if said sleeve is rotated from said adjusted position to said predetermined position and then returned toward said adjusted position, said sleeve may be positioned and locked in its pre-set adjusted position by interengagement of said locating pins.

5. A locking adjustable support, for printing press rollers or the like, comprising, in combination, a substantially cylindrical trunnion arranged to be secured relative to the press frame, the inner end of said trunnion having a diametric slot arranged to conformingly slidably receive the bearing means of a press roller; and eccentric sleeve rotatably mounted on said trunnion and having a circular surface portion on its axially inner end eccentric to said trunnion and extending axially of said slotted inner end thereof for engagement with a bearing means in said slot to adjust said bearing means along said slot responsive to relative rotation of said sleeve on said trunnion to an adjusted position; said sleeve circular portion having a peripherally extending slot opening axially through the inner end of said sleeve and of an arcuate extent substantially equal to that of said diametric slot whereby, when said sleeve is angularly adjusted to a predetermined position in which said slots are radially aligned, a bearing means may be inserted into and removed from said diametric slot; said eccentric sleeve being formed with a circumferentially extending slot having an angular extent of less than 180°; a second sleeve embracing said eccentric sleeve, said second sleeve having a bore therethrough radially aligned with said circumferentially extending slot; a pin disposed through the bore in said second sleeve and extending through said circumferentially extending slot, the inner end of said pin being threaded into said trunnion; said pin, in cooperation with said circumferentially extending slot, limiting angular movement of said eccentric sleeve relative to said trunnion, and said pin, when tightened, clamping said second sleeve against said eccentric sleeve to lock said eccentric sleeve in angularly adjusted position; and position setting means angularly adjustable on said trunnion in accordance with the adjusted position of said eccentric sleeve and cooperating with the latter to set said adjusted position thereof whereby, when said eccentric sleeve is rotated from its adjusted position to said predetermined position, and then returned toward said adjusted position, said position setting means will effect accurate resetting of said eccentric sleeve in its previous adjusted position.

6. A locking adjustable support, for printing press rollers or the like, comprising, in combination, a substantially cylindrical trunnion arranged to be secured relative to the press frame, the inner end of said trunnion having a diametric slot arranged to conformingly slidably receive the bearing means of a press roller; an eccentric sleeve rotatably mounted on said trunnion and having a circular surface portion on its axially inner end eccentric to said trunnion and extending axially of said slotted inner end thereof for engagement with a bearing means in said slot to adjust said bearing means along said slot responsive to relative rotation of said sleeve on said trunnion to an adjusted position; said sleeve circular portion having a peripherally extending slot opening axially through the inner end of said sleeve and of an arcuate extent substantially equal to that of said diametric slot whereby, when said sleeve is angularly adjusted to a predetermined position in which said slots are radially aligned, a bearing means may be inserted into and removed from said diametric slot; said trunnion having a reduced axial extension on its outer end, and being formed with an axial bore therethrough; said extension being arranged to seat in a corresponding recess in mounting means for said

support, and said axial bore receiving a fastening means for securing said trunnion to said mounting means; and position setting means angularly adjustable on said trunnion in accordance with the adjusted position of said sleeve and cooperable with said sleeve to re-set said sleeve to said adjusted position after said sleeve has been turned from said adjusted position to said predetermined position and then turned back toward said adjusted position.

7. A locking adjustable support, for printing press rollers or the like, comprising, in combination, a substantially cylindrical trunnion arranged to be secured relative to the press frame, the inner end of said trunnion having a diametric slot arranged to conformingly slidably receive the bearing means of a press roller; an eccentric sleeve rotatably mounted on said trunnion and having a circular surface portion on its axially inner end eccentric to said trunnion and extending axially of said slotted inner end thereof for engagement with a bearing means in said slot to adjust said bearing means along said slot responsive to relative rotation of said sleeve on said trunnion to an adjusted position; said sleeve circular portion having a peripherally extending slot opening axially through the inner end of said sleeve and of an arcuate extent substantially equal to that of said diametric slot whereby, when said sleeve is angularly adjusted to a predetermined position in which said slots are radially aligned, a bearing means may be inserted into and removed from said diametric slot; said trunnion being formed with an axial extension on its outer end, and with an axial bore therethrough; a plate formed with a recess to seat said extension; a fastening device extending through said axial bore and engaged in said plate to secure said trunnion to said plate; means for rotatably securing said plate to a part of the press frame, said means being located in spaced relation to said recess and providing for oscillation of said plate relative to the press frame; whereby said support may be angularly adjusted, about the support point of said plate as an axis, to adjust the contact of a press roller with a pair of cooperating press rollers mounted in the press frame; and position setting means angularly adjustable on said trunnion in accordance with the adjusted position of said sleeve and cooperable with said sleeve to re-set said sleeve in said adjusted position after said sleeve has been turned from said adjusted position to said predetermined position and then turned back toward said adjusted position.

8. A locking adjustable support, for printing press rollers or the like, comprising, in combination, a substantially cylindrical trunnion arranged to be secured relative to the press frame, the inner end of said trunnion having a diametric slot arranged to conformingly slidably receive the bearing means of a press roller; an eccentric sleeve rotatably mounted on said trunnion and having a circular surface portion on its axially inner end eccentric to said trunnion and extending axially of said slotted inner end thereof for engagement with a bearing means in said slot to adjust said bearing means along said slot responsive to relative rotation of said sleeve on said trunnion to an adjusted position; said sleeve circular portion having a peripherally extending slot opening axially through the inner end of said sleeve and of an arcuate extent substantially equal to that of said diametric slot whereby, when said sleeve is angularly adjusted to a predetermined position in which said slots are radially aligned, a bearing means may be inserted into and removed from said diametric slot; said trunnion being formed with a diametrically extending bore; a slide in said last named bore having one end engageable with said inner circular surface portion of said eccentric sleeve; the other end of said slide being formed with a recess; a second slide positioned in said recess and extending radially therefrom; spring means interposed between said second slide and said first slide and effective to bias said second slide to engage said inner circular surface portion of said eccentric sleeve;

said first slide having an axial extension projecting therefrom toward the inner end of said trunnion and arranged to overlie a bearing means positioned within said inner circular surface portion of said eccentric sleeve and position setting means angularly adjustable on said trunnion in accordance with the adjusted position of said sleeve and cooperable with said sleeve to set said adjusted position thereof whereby, when said sleeve is turned from said adjusted position to said predetermined position and then returned toward said adjusted position said position setting means will assure registry of said sleeve in its said adjusted position.

9. The locking adjustable support, as claimed in claim 8, including a guide pin secured at one end to said second slide and extending through a small diameter opening in the bottom of said recess.
